Des. 185,831
Patented Aug. 4, 1959

185,831

WALL MOUNTED AQUARIUM

Irvin N. Kaake, East Detroit, Mich.

Application August 21, 1958, Serial No. 52,330

Term of patent 14 years

(Cl. D91—2)

Fig. 1 is a perspective view of a wall mounted aquarium showing my new design on a slightly enlarged scale;

Fig. 2 is a front elevational view of the aquarium shown in Fig. 1;

Fig. 3 is an end elevational view; and

Fig. 4 is a sectional view taken substantially on the plane indicated by line IV-IV of Fig. 2.

I claim:

The ornamental design for a wall mounted aquarium, substantially as shown.
